UNITED STATES PATENT OFFICE.

WILLIAM S. GUBELMANN, OF BUFFALO, NEW YORK.

DESIGN FOR A BICYCLE-FRAME.

SPECIFICATION forming part of Design No. 26,899, dated April 13, 1897.

Application filed January 18, 1897. Serial No. 619,687. Term of patent 14 years.

To all whom it may concern:

Be it known that I, WILLIAM S. GUBELMANN, a citizen of the United States, residing at Buffalo, in the county of Erie and State of New York, have invented and produced a new and original Design for Cycle-Frames, of which the following is a specification, reference being had to the accompanying drawing, forming a part thereof.

This design relates to the configuration of a cycle-frame, the accompanying drawing being a perspective view of a cycle-frame embodying my design.

The distinctive feature of my design consists in the peculiar shape of the front ends of the upper and lower rear forks.

Referring to the drawings, A represents the steering-head; B, the crank-hanger; D, the lower front bar, extending from the head to the hanger; E, the saddle-post, extending upwardly from the hanger; and F, the upper front bar extending from the head to the upper end of the saddle-post.

G G are the two bars which constitute the upper rear fork and which extend from the rear axle-supports *h* to the upper end of the saddle-post. Each of these bars consists of a lower straight portion *g*, which extends forwardly and upwardly from the rear end of the bar, an upper straight portion *g'*, offset inwardly beyond the plane of said lower portion, and an intermediate portion *g²*, which connects said straight portions and which is reversely curved or of ogee form, as shown.

The upper straight portions *g'* converge up-

wardly and rest against each other, as distinguished from fork-arms which are separated at their upper portions by an intervening space, forming practically a single bar, while at the same time preserving the appearance of two separate and distinct bars, as shown in the drawing.

I I represent the two bars which constitute the lower rear fork and which extend from the rear axle-supports to the hanger. Each of these bars consists of a rear straight portion *i*, which extends forwardly from the rear end of the bar, a front straight portion *i'*, offset inwardly beyond the plane of said rear portion, and an intermediate portion *i²*, which connects said straight portions and which is reversely curved or of ogee form, as shown. The front straight portions *i'* are parallel and rest against each other, forming practically a single bar, while at the same time preserving the appearance of two separate and distinct bars, as shown in the drawing.

I claim as my invention—

1. The design for the upper rear fork of a cycle-frame, substantially as herein shown and described.

2. The design for the lower rear fork of a cycle-frame, substantially as herein shown and described.

Witness my hand this 11th day of January, 1897.

WILLIAM S. GUBELMANN.
